UNITED STATES PATENT OFFICE.

GEORGE E. NORRIS, OF COLUMBUS, OHIO, ASSIGNOR TO THE PERFECTION MORTISE MACHINE COMPANY, OF COLUMBUS, OHIO, A CORPORATION OF OHIO.

MORTISING-MACHINE.

1,356,394.

Specification of Letters Patent. Patented Oct. 19, 1920.

Application filed March 20, 1915. Serial No. 15,955.

To all whom it may concern:

Be it known that I, GEORGE E. NORRIS, a citizen of the United States, residing at Columbus, in the county of Franklin and State of Ohio, have invented certain new and useful Improvements in Mortising-Machines, of which the following is a specification.

My invention relates to mortising machines of the rotary cutter type, certain improvements of which are specifically adapted for the rotary and oscillating cutter type. My machine is so constructed that it may be readily applied to its work and the mortise completed in a minimum amount of time.

15 The main object of my invention resides in the provision of a structure whereby the ends of the mortise are clean cut throughout their entire depth. This I accomplish by a structure so arranged that the rotating cutter tool is held in a stationary position as regards its back and forth movement for a certain time interval at the end of its stroke and during its continued rotation. This, broadly, forms the essence of my invention.

25 although the specific structure for accomplishing the same is also regarded by me as novel.

Further objects of my invention reside in a structure for imparting an infeed movement to the bit, means for varying the length of the back and forth movement of the bit itself and other improved structures as will be apparent from the detailed description to follow.

35 In the accompanying sheets of drawings, I have represented the preferred embodiment of my invention and in these drawings similar characters of reference designate corresponding parts throughout the several

40 views.

Figure 1 is a view in front elevation of my machine,

Fig. 2 is a view in rear elevation of my machine,

45 Fig. 3 is an end view looking from the left of Fig. 2,

Figs. 4 and 5 are sections taken on line 4-4 of Fig. 3 and looking in the direction of the arrows, showing the mechanism by 50 which the cross travel of the bit is temporarily interrupted at each end of its stroke.

Fig. 6 is a fragmentary section taken on line 6-6 of Fig. 3,

Fig. 7 is a detail view of the mechanism for regulating the length of the linear travel 55 of the bit shown detached,

Fig. 8 is a similar view showing the same mechanism in another position or the opposite extreme position from that shown in Fig. 7.

Fig. 9 is a top plan view of a portion of the infeed mechanism shown in Fig. 7,

Fig. 10 is a top plan view of the same structure shown in Fig. 8,

Fig. 11 is a section taken on line 11-11 60 of Fig. 9,

Fig. 12 is a detail view in perspective of the inside of the link element shown in Figs. 9 and 10,

Fig. 13 is a detail view in perspective of 70 the mechanism for holding the carriage in its position on the main framework,

Fig. 14 is a vertical longitudinal section of the structure shown in Fig. 13 and represented by line 14-14 of Fig. 2,

Fig. 15 is a detail view of a portion of the linear reversing mechanism shown detached,

Fig. 16 is a similar view showing the same mechanism in its opposite extreme position from that shown in Fig. 15,

Fig. 17 is a detail view in perspective of 80 one of the lever elements shown in Figs. 15 and 16,

Fig. 18 is a detail view in perspective of one of the elements shown in Figs. 15 and 16, 85

Fig. 19 is a detail view in perspective of one of the elements shown in Figs. 15 and 16,

Fig. 20 is a detail view in perspective of another one of the elements shown in Figs. 15 and 16,

Fig. 21 is a view of the bit supporting structure itself in side elevation,

Fig. 22 is a vertical longitudinal section of the structure shown in Fig. 21,

Fig. 23 is a detail view in perspective of 90 one element forming the bit supporting structure,

Fig. 24 is a similar view of another element forming the bit supporting structure,

Fig. 25 is a detail view in perspective of 100 the upper end of the bit,

Fig. 26 is a detail view in perspective of

an adjusting block used by me for regulating the throw of the bit, and,

Fig. 27 is a detail view in perspective of another element forming a portion of the bit supporting structure.

As shown in the drawings there is a main frame comprising a base 1, rigid side rods 2, an upper cross piece 4, supporting wires 5 and clamping bolts 3. The main carriage

- 10 frame 7 slides on the rods 2 by means of bearings 6. A hub bored in the carriage frame receives the shaft 8 rigidly bearing the main driving gear 9 operated in one direction only by oppositely disposed handles 15 10 and prevented from reverse rotation by a spring actuated pawl or lock bolt 9^a engaging notches 9^a.

The major gear 9 has teeth on one side meshing with the pinion 23 having a key 20 engaging the keyway 22 of the bit shank for rotating the bit 16 and with the pinion 57 operating mechanism to move the bit back and forth and to give it its infed. The bit itself is mounted in the supporting member 17 (see Fig. 23) having a cut out portion 18 and a cap or hood portion 19 into which the upper end of the bit projects and where it is held by a cotter pin 25 engaging the circumferential groove 20. The bit also rotates in the bearing members 30 13, 14 and 15 of the supplemental supporting element 12 which members project into the cut out portion 18. The element 12 is pivotally mounted by its hub 11 on the shaft 8. The supporting element 17 has its lower end pivotally connected to the transverse carriage 33 (see Fig. 27) by a pin passing through the apertures 38 of the carriage and the hubs 37 of the support 17. 35 40 The transverse carriage 33 has ears 34 sliding on cross rods 32 supported at their ends in ears 31 at the lower end of the main carriage 7. As the element 17 is pivotally connected to the transverse carriage and the element 12 is pivoted to the shaft 8 it follows that these two elements constituting the bit support must be so mounted with respect to each other as to permit of relative longitudinal movement as the machine 45 50 is operated.

The cross feed mechanism.

The cross-feed of the bit is produced by a feed screw 39 rigidly attached to the transverse carriage 33 and which passes through spaced bearings 40 and 41 at one of the lower corners of the carriage 7. Between the bearings 40 and 41 and threaded on the cross feed screw 39 is the worm gear 55 60 nut 42 operated by the worm 43 near the lower end of the sleeve 44 whose lower end finds a bearing at 46 on the carriage 7. The sleeve 44 incases the lower end of shaft 47 on which is splined the sleeve 51 bearing

the oppositely faced beveled gears 52 and 53 engaged alternately by the beveled pinion 54 on inner end of shaft 55 journaled at 56 in the main carriage 7 and on the outer end of which is spur pinion 57 meshing with the teeth of the main drive wheel as hereinbefore stated.

Dwell of bit carriage.

The shaft 47 has a reduced lower end 45 which finds a bearing; see Figs. 4 and 5, 75 in the lower end of the sleeve 44 which bears a pin 49 engaging alternately shoulders at opposite ends of the thread 48 on said shaft which may therefore revolve in either direction independently of the sleeve 80 until the pin 49 reaches the alternate ends of the thread 48 when the shaft 47 carries the sleeve 44, revolving the worm nut causing the transverse travel of the screw shaft 39 and the bit frame 33. The bit therefore 85 revolves without transverse travel while the shaft 47 travels longitudinally the length of the screw thread 48 and thereby the corners of the mortise are cut clean.

Reversal of bit carriage.

As the bit travels transversely by the reciprocatory travel of the transverse carriage 33 its shaft swings the supporting members 12 and 17 in which said shaft has bearings. 95 The back of the member 12 carries guide strips 77 leaving a way or groove 78 into which projects from the slide block 84 the pin 85. This block has threaded engagement with the screw rod 82 both of which are received in the slot 81 of the bar 79 pivoted at 80 to the carriage 7. As the bar 79 is swung by the swinging of the bit shaft support 12 it also swings by means of the link 89 the lever 73 also pivoted to the carriage 7. Projecting from the lever 73 is an arm 75 forked to form fingers 76 embracing the short arm 67 of the bell crank 65, Figs. 1, 15 and 16, rigidly mounted on the rocking stub shaft 66 mounted in the carriage 7. The short arm 67 has an arrow-head-shaped end 68 against which the double inclined end 72 of the lever 69 pivoted to the frame at 70 is held in contact by the coiled spring 71 attached to the opposite 115 end of the said lever 69 and to the carriage frame. The formation of 68, 72 and the arrangement of the lever and spring being such therefore as to normally tend to hold the short arm 67 at one or the other extreme of its movement also tends to have a corresponding control on the long arm of the lever which alternately engages the jaws 64 extending from the shifting bar 60 mounted on the carriage 7 by shoulder 125 screws 59 extending through slots 61. The shifting member 60 also carries a yoke portion 62 engaging between annular ribs 63

on the sleeve 51. As appears the formation of the arrow faces 68 and coacting faces 72 of the lever are such that on the passage of the arrow-point over the angle formed by the faces 72 the spring 71 will cause a quick throw of the bell crank lever and shifting of the gear sleeve 51.

Adjustment of length of stroke and cut.

10 The screw 82 has a milled head 83, the turning of which adjusts the nut 84 in the slot 81 and its pin 85 in the way 78 of the bit shaft support 12. As the point of attachment of the link 89 to the lever 79 remains constant, it is evident that the rate 15 of travel of the lever 79 and the link 89 and connected shifting mechanism to that of the bit shaft will be decreased by raising the nut 84 and increased by lowering it, that is, 20 by bringing it nearer to or removing it farther from the pivot point of the bit shaft support 12. Hence the length of stroke and cut will be reduced by lowering the nut 84 and increased by raising said nut in the 25 slot 81.

It will be noted by reference to Figs. 1, 15, 16 and 17 that the space between the fingers 76 exceeds the width of the short arm 67 of the bell-crank lever sufficiently to allow the 30 arrow-head 68, when it has moved over one of the faces 72 and has passed the point of the co-acting faces 72, to continue its movement into full engagement with the opposite face, under the action of the spring 71 and complete the throw of the long arm 65 and thereby effect that of the shifting member 60 and the gear sleeve 51 and in either direction.

It will also be noted that the distance between the jaws 64 is sufficient to allow of substantially the first half of the movement of the arm 67 of the bell-crank lever in either direction under the action of the fingers 76, or until the arrow-head 68 reaches the apex of the faces 72, without any operation of the shifting member 60.

It is therefore seen that the reversal of the bit carriage is brought about at the end of each of such oscillatory travel through 50 connection with the bar 79, link 89, lever 73, bell-crank lever 65, bar 60, shifting the gear sleeve 51 and the direction of rotation of the shaft 47, sleeve 44 and worm nut 42 which reciprocates the feed screw 39 attached to the reciprocating carriage and that accidental shifting of members 60 is prevented.

Mechanism for preventing premature disengagement of gear 54 with gears 52 and 53.

60 An arm 66^b, like the bell-crank lever 65, is rigid on the rock shaft 66. As the arm 67 of the bell-crank lever is rocked to the right, see Figs. 1 and 15, a lug 66^a on arm 66^b engages the upper side of a lug 60^a on 65 the shifting member 60 and maintains its

engagement until the arrow-head 68 has reached the apex of the faces 72 when, passing out of such engagement, it allows the raising of the shifting member 60. Likewise, on the reverse movement, see Fig. 16, 70 or swinging to the left, of the arm 67 and 66^b, the lug 66^a engages the lower face of 60^a to prevent the dropping of the sleeve 51 and maintains such engagement until the arrow-head 68 reaches the apex of the faces 75 72 in its then opposite movement.

The in-feed mechanism.

A threaded rod 25 passes at 26 loosely through the upper cross piece 4 of the main frame. To the cross piece are pivoted levers 27 which have their lower ends provided with fingers or half nuts 29, the latter being held normally in engagement with the threaded rod by means of a spring 30 which 80 connects the lower ends of said levers 27. By pressing together the hand levers, therefore, the mortising frame or carriage may be adjusted up and down since the lower end of the rod 25 is swiveled as at 24 in 90 said frame.

To impart a gradual downward movement to the carriage 7 and consequently the bit 16 during mortising operations of the latter, the rod 25 carries at its lower end a 95 fixed gear 25^a, which latter is adapted to be rotated and with it the rod 25 in one direction only by means of a rack member 90. This member is of substantially oval shaped formation and is situated to embrace or 100 surround the gear 25^a, oppositely disposed sets of rack teeth 91 being disposed on the inner sides of the rack member for alternate engagement with the gear 25^a whereby the rod or screw 25 will be caused to rotate in 105 an in-feeding direction irrespective of the direction of rectilinear travel of the member 90.

In order to effect the reciprocation of the member 90 and to control the shifting of 110 its rack teeth into mesh with the gear 25^a, the lever 73 has its free end provided with an elongated slot 103 in which is adjustably mounted a pin 102 carried by one end of a link or tie member 101, thus upon the 115 oscillation of the lever 73, effective by its connection 89 with the bit supporting structure, back and forth movement will be imparted to the link 101. The other end of said link 101 is pivotally connected as at 100 120 to the lower end of a lever 97, which is pivoted intermediately of its length upon the carriage 7, as is indicated by the numeral 99, and the lever 97, in turn, has its upper end pivotally connected as at 98 with a horizontally disposed connecting member 96. This member has its end, opposite to its pivotal connection 98 bent angularly and pivotally connected as at 95 with the rack member. Thus, it will be manifest that through 125 130

the medium of the articulately connected levers described, the oscillation of the lever 73 to the left, see Figs. 7 and 8, will result in movement of the rack member to the right and vice versa, thereby effecting the rotation of the gear 25^a and the gradual in-feeding movement in a lowering direction of the screw 25.

However, in order to shift the rack member 90 laterally upon the completion of its reciprocatory strokes, so that it will disengage one set of its teeth 91 from the gear 25^a and throw its opposite set of teeth into mesh with said gear, said rack member is further pivoted as at 93 upon the free end of the link 92, which latter, in turn, is pivoted at 94 upon a fixed portion of the carriage 7. The link 92 by reason of its connection with the rack member will serve to support the latter for reciprocatory movement and will travel in unison therewith. Motion of the link 92 is normally retarded by providing its under surface with a plurality of depressions or sockets 105 into which is resiliently projected a ball 104, said ball being urged toward the sockets and seated therein by means of a coil spring 106, which is confined in a bore formed in the carriage 7. Through the use of this construction movement of the link 92 will be retarded or restricted, and before being oscillated the resistance offered by the ball 104 must be overcome. Thus, when the connecting member 96 initially responds to the actuating movement of the lever 97, said rack member will rock about its pivot 93, since the link 92 is held stationary by the ball mechanism 104, thereby causing the gear 25^a to mesh with the set of rack teeth 91 opposite to that set with which it was in mesh during the preceding movement of the rack member. By engaging the gear 25^a further oscillatory movement of the rack member is prevented and, hence, the movement of the connecting member 96 is imparted conjointly to the rack member 90 and its supporting link 92 so as to cause the reciprocation of said rack member, the consequent rotation of the gear 25^a and oscillatory movement on part of the link 92, the latter operating against the resistance offered by the spring pressed ball 104. When the end of this stroke of the rack member has been reached, said member will again pivot about the point 93 in the manner above described, and will thus throw its other set of rack teeth 91 into engagement with the gear 25^a, thus causing the reciprocatory movement of the rack member to impart a rotary movement in one direction to the screw or rod 25 and consequently an in-feed movement to the bit structure itself.

From the foregoing description, it will be apparent that I have provided a machine

embodying several novel features of construction, among these being particularly, the structure for giving the in-feed to the bit and also the structure for regulating the length of cut or its cross feed. Further, I have provided a structure wherein the depth cut is clean, perfect corners being thereby made. This latter is accomplished by causing a predetermined number of revolutions of the bit itself while it remains in stationary position as regards its back and forth movement at the end of each stroke.

What I claim as patentable is:

1. A mortising machine comprising a frame work, a bit, means for rotating said bit, means for moving said bit transversely during its rotary movement, means for automatically reversing the transverse travel of said bit at the end of its stroke during the continued operation of the machine, and means for causing said bit to remain stationary for at least one complete revolution at the end of each stroke before the reversal of transverse movement takes effect. 75

2. A mortising machine comprising a frame work, a bit, means for rotating said bit, means for moving said bit transversely during its rotary movement, means for automatically reversing the transverse travel of said bit at the end of its stroke during the continued operation of the machine and means for delaying the transmission of the reversing movement for at least one complete revolution of said bit. 90

3. A mortising machine comprising a frame work, a bit, means for rotating said bit, means for moving said bit transversely during its rotary movement, means for automatically reversing the transverse travel of said bit at the end of each stroke during the continued operation of the machine, and a lost motion driving connection between said bit and said reversing means permitting said bit to remain stationary as regards its transverse movement for at least one revolution of the bit at the end of each stroke. 105

4. A mortising machine comprising a framework, a bit, a cross feed screw co-operating with said bit, a worm wheel co-operating with said screw, a worm arranged to engage said wheel, a drive shaft for said worm, means for rotating said shaft, means for changing its direction of rotation, and a lost motion connection between said shaft and one of its co-operating parts whereby the direction of rotation of said screw is not simultaneously changed with the reversal in direction of said shaft. 115

5. A mortising machine comprising a framework, a bit, a cross feed screw co-operating with said bit, a worm wheel co-operating with said screw, a sleeve provided with a worm arranged to engage said wheel, a drive shaft slidably within said sleeve, said shaft being provided with a threaded 120

portion, means for driving and changing the direction of rotation of said shaft, and a pin connection carried by said sleeve and operating in the threads of said shaft to 5 key said shaft and said sleeve together at the ends of said threaded portion.

6. A mortising machine comprising a framework, a carriage slidably mounted on 10 said framework, a bit, a bit supporting structure carried by said carriage, means for moving said bit and its supporting structure back and forth, means for rotating said bit, an infeed screw, a pinion carried by 15 said screw, a rack structure having oppositely disposed rack faces, one face of which is normally in mesh with said pinion, means for imparting rectilinear movement to said rack structure, and means for disengaging one rack face from said pinion and engaging the other rack face therewith for 20 each reversal of direction of reciprocation of the rack.

7. A mortising machine comprising a framework, a carriage slidably mounted on

said framework, a bit, a bit supporting 25 structure carried by said carriage, means for moving said bit and its supporting structure back and forth, means for rotating said bit, an infeed screw, a pinion carried by 30 said screw, a rack member embracing said pinion and having inside rack faces facing each other, a link pivoted at one end to said carriage and to said rack member at its other end, means pivoted to said rack member on the opposite side of said pinion from said 35 link pivot connection for imparting rectilinear movement thereto, and means for retarding the free movement of said link and said rack member over each other, said last named means operating between the two 40 pivot points of said link.

In testimony whereof I affix my signature in presence of two witnesses.

GEORGE E. NORRIS.
